United States Patent Office

Des. 183,144
Patented July 1, 1958

183,144

CLOCK

Ben Rubin, Chicago, Ill.

Application July 11, 1956, Serial No. 42,212

Term of patent 14 years

(Cl. D42—7)

Fig. 1.

Fig. 2.

Fig. 3.

Figure 1 is a front elevational view of the clock, showing my new design;

Figure 2 is a top plan view thereof, and

Figure 3 is a side elevational view thereof.

The clock works have been omitted in Figure 3 for convenience of illustration.

The dominant features of the design reside in the portion shown in full lines.

I claim:

The ornamental design for a clock, as shown and described.
